UNITED STATES PATENT OFFICE.

JOHN H. KELLOGG, OF BATTLE CREEK, MICHIGAN.

DESIGN FOR A DENTAL IMPLEMENT.

59,230.

Specification for Design.

Patented Oct. 4, 1921.

Application filed February 28, 1920. Serial No. 362,126. Term of patent 14 years.

To all whom it may concern:

Be it known that I, JOHN H. KELLOGG, a citizen of the United States, and a resident of Battle Creek, county of Calhoun, State of Michigan, (whose post-office address is Battle Creek, Michigan, c/o Battle Creek Sanitarium,) have invented a new, original, and ornamental Design for a Dental Implement, of which the following is a specification, reference being had to the accompanying drawing, forming a part thereof.

Fig. II is a perspective view of an implement, closed, showing my new design.

I claim:

The ornamental design for a dental implement as shown.

JOHN H. KELLOGG.
